UPHOLSTERY CONSTRUCTION

Rutledge A. Parker, Max Kiessling, and Max J. Kiessling, Waterbury, Conn., assignors to Parker Products Corporation, Waterbury, Conn., a corporation of Connecticut

Application November 25, 1940, Serial No. 367,022

4 Claims. (Cl. 155—179)

This invention relates to upholstered furniture and more particularly to a "non-sag" upholstery cushion construction wherein coiled cushion springs will be supported by a plurality of crossed metallic strips of an improved form.

One object of this invention is to provide a construction of the above nature in which the lower convolution of each cushion spring is secured to at least one of said strips by a pair of circular raised and depressed loops, and said coil is locked tightly in operating position by longitudinally stretching said strip.

Another object is to provide an improved "non-sag" upholstery construction of the above nature which will be relatively inexpensive to manufacture, simple in construction, compact, ornamental in appearance, and very efficient and durable in use.

With these and other objects in view, which will appear as the description proceeds, there have been illustrated in the accompanying drawing two forms in which the invention may be conveniently embodied in practice.

In the drawing:

Figure 1 is a top plane view of a chair seat embodying the invention with part of the upholstery material removed to expose the supporting springs therebeneath.

Figure 2 is an enlarged broken cross-sectional view of the same taken on the line 2—2 of Figure 1.

Figure 3 is an enlarged top plan view of one of the cushion spring-supporting metallic strips, showing its relation to the springs supported thereby, and a supporting cross strip.

Figure 4 is an enlarged side view of a portion of one of the stretchable spring-supporting strips before it has been assembled in operating position.

Figure 5 is a top plan view of the spring-supporting strip shown in Figure 4.

Figure 6 is an enlarged transverse sectional view of said strip taken on the line 6—6 of Figure 5, showing the upstanding and depressed loop sections.

Figure 7 is a side view of a modified form of spring supporting strip having indicating indented sections between the successive loop sections.

Figure 8 is a top plan view of the same.

Figure 9 is an enlarged transverse sectional view on the line 9—9 of Figure 7, taken through one of the indented sections.

Referring now to the drawing wherein like reference numerals designate like parts throughout the several views, the numeral 10 denotes an open

rectangular wooden seat frame of an article of upholstered furniture, such as a chair, supported on four legs or feet 11. A plurality of coiled cushion springs 12, preferably conical in form, are secured at their upper ends in the usual manner, by means not shown, to the upholstery seat covering 13, and said springs are preferably arranged in aligned rows within the frame 10 to properly support the upholstery covering 13. The springs 12 are in turn supported by two rows of crossed parallel metal strips 14 and 14a, secured at their ends to said frame 10.

The strips 14 may be made of any suitable strong metal having sufficient tensile strength to prevent said strips from stretching during use. The first form of stretchable metallic strip 14 shown in Figures 1 to 6, is provided with a series of cooperating upstanding loops 15, and depressed loops 16 and 17 arranged in groups which are uniformly spaced apart the entire length of said strip. The loop 15 of each group is struck upwardly from the center of the strip 14 while the loops 16 and 17 are struck downwardly from the strip 14, one on either side of the loop 15. Intermediate each group of loops 15, 16, and 17, the strip 14 is provided with a round hole 18 which serves to locate fastening members, such as screws or nails 19, whereby the strip 14 may be securely attached to the frame 10. In the modified form of strip 20, shown in Figures 7 to 9 inclusive, indicating, raised, indented points 21, are substituted for the holes 18 of the first form for receiving the fastening members 19, which may be driven through said sections 21 to attach said strip to the frame 10. The indented points 21 are raised upwardly from the surface of the metal strip and are adapted to be easily punctured by the attaching nail or screw when the latter is driven through it by the blows of a hammer. The raised indented points also serve as indicating means to insure the placing of the strip with its bottom surface against the furniture frame. The strips 14a are made plain and unstretchable, having no raised or depressed loops, but are provided merely with spaced apertures 18 or indentations 21 for the attaching nails or screws 19.

Operation

In operation, one end of each stretchable strip strip 14 (or 20) will first be nailed, screwed, or otherwise permanently attached to the front frame member 22, as shown at the left in Figure 2, leaving the opposite ends of said strips 14 loose. The crossing plain strips 14a will then be inserted in the position shown in Figure 1, leaving both

ends thereof loose. The lowermost convolution 23 of each coil spring 12 will then be placed upon the strips and threaded through the groups of loop sections 15, 16, and 17 of the stretchable strips 14, with the loops 15 uppermost and lying above the convolution 23, and the loops 16 and 17 underneath it. Each group of loops 15, 16, and 17 of the stretchable strips 14 which are located under diametrically opposite points on the coils 23 will then be stretched and flattened by a special pulling tool, not shown. The unoccupied loops 15, 16, and 17, will thus be forced back into flat alignment with the remainder of the strip 14 and the coil-filled loops will frictionally engage opposite sides of the coil 23 embraced thereby. The flat remaining portion of said strip 14 will of course not be stretched. The free ends of the stretchable strips 14 will next be securely fastened to the rear frame member 24 by screw or nails 19 driven through the holes 18, or through the indented points 21, as the case may be. The plain cross strips 14a will finally be nailed at both ends, without stretching to the side frame members 26 and 27. As shown in Figure 1, the strips 14 preferably cross each other at right angles to the center axis 25 of each spring 12, and the bottom convolution 23 of each spring will be supported upon said crossed strips at four points, thus providing "four point" contacts therefor.

One advantage of the present invention is that the operation of stretching the groups of coil-embracing loops of each stretchable strip 14 will cause said loops to bind tightly upon the lower convolution of the coil springs, thus effectively locking them from shifting out of position. The stretching process also straightens the unused loops 15, 16, and 17, so that there will be no possibility of further stretching of the strips 14 (or 20), during use by the weight of persons using the article of furniture. A further advantage is that no rattling can occur at the attachment points, because all looseness between the spring coils 23 and the strips 14 (or 20), has been eliminated.

It will be understood that it is within the scope of the present invention to employ the construction herein disclosed on mattresses, box springs, bed springs, etc., in which case the crossed metal strips will be located on both the top and bottom surfaces thereof, above and below the coil springs located therein.

It will also be understood that if desired, the plain cross strips 14a disclosed herein, may be omitted and replaced by strips of webbing within the spirit of the invention.

While there have been disclosed in this specification two forms in which the invention may be embodied in practice, it is to be understood that these forms are shown for the purpose of illustration only, and that the invention is not to be limited to the specific disclosures, but may be embodied in various other forms without departing from its spirit. In short, the invention includes all the modifications and embodiments

coming within the scope of the following claims.

Having thus fully described the invention, what is claimed as new and for which it is desired to secure Letters Patent, is:

5. 1. The process of manufacturing an upholstery construction which comprises: securing to an open frame of an article of furniture a pair of crossed narrow metallic strips, one of which has a plurality of groups of stretchable upstanding and depressed loop sections, inserting the lowermost convolution of a coil spring within a pair of said groups of loop sections for supporting said spring upon said strips, and frictionally locking said spring to said strips by permanently stretching said strip having the loop sections beyond the elastic limit of the metal thereof to cause said loops to flatten and tightly embrace the lowermost convolution of said spring.
10. 2. The process as defined in claim 1 in which some of said groups of loop sections are unoccupied by coil spring convolutions, and in which the step of stretching said strip causes said unoccupied loop sections to flatten out and prevent any possibility of further stretching of said strips during use.
15. 3. The process of manufacturing an upholstery construction which comprises: placing upon an open frame of an article of furniture a pair of crossed metallic strips, one of which has a plurality of groups of stretchable upstanding and depressed loop sections, and both of which have a plurality of attaching apertures, inserting the lowermost convolution of a coil spring within a pair of said groups of loop sections for supporting opposite sides of said spring, frictionally locking said spring in position by permanently stretching the strip having said loop sections to cause said loops to flatten and tightly and frictionally embrace the lowermost convolution of said spring, and finally securing said crossed strips to said open frame by driving attaching means through the apertures of said strips in alignment with the edges of said frame.
20. 4. The process of manufacturing an upholstery construction which comprises: placing upon an open frame of an article of furniture a pair of crossed metallic strips, one of which has a plurality of groups of stretchable upstanding and depressed loop sections, and both of which have a plurality of attaching sections, inserting the lowermost convolution of a coil spring within a pair of said groups of loop sections for supporting said spring, frictionally locking said spring in position by permanently stretching the strip having said loop sections to cause said loops to flatten and tightly and frictionally embrace opposite sides of the lowermost convolution of said spring, and finally securing said crossed strips to said open frame by driving attaching means through the sections of said strips in alignment with the edges of said frame.
